(57) **CLAIM**

The ornamental design for a horticultural therapy apparatus, as shown and described.

DESCRIPTION

FIG. 1 is a perspective view of a horticultural therapy apparatus showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken line defines the bounds of the claimed design and forms no part thereof and the lightened portions of the horticultural therapy apparatus form no part of the claimed design.

1 Claim, 7 Drawing Sheets
